BY his ATTORNEY.
A.M. Carlsen.

UNITED STATES PATENT OFFICE.

GEORGE CUFF, OF POYNETTE, WISCONSIN.

TRACTION-ENGINE.

1,221,975.

Specification of Letters Patent. Patented Apr. 10, 1917.

Application filed April 24, 1913. Serial No. 763,294.

To all whom it may concern:

Be it known that I, GEORGE CUFF, a citizen of the United States, residing at Poynette, in the county of Columbia and State 5 of Wisconsin, have invented a new and useful Traction-Engine, of which the following is a specification.

This invention relates to traction engines; and the principal object is to provide 10 such engines with an efficient and durable attachment by which to haul heavily loaded vehicles, or other loads drawn by the engine up hills or over rough or soft parts of a road. The invention may be considered as 15 a further improvement of the traction engine described in my United States Patent No. 825,520, issued July 10, 1906.

In the accompanying drawings—

Figure 1 is an enlarged view of the attachment removed from under the platform of the traction engine where it is usually secured. Fig. 2 is a side elevation of the attachment shown in Fig. 1 with the platform of the traction engine restored.

Referring to the drawings by reference numerals, 5 designates the engineer's platform of any ordinary traction engine (not shown). A valve (not shown) admits steam downward through a pipe 9 to the attachment which will now be described.

The attachment is designed to be secured underneath the platform 5, and involves a frame preferably made of channel iron side bars 10, which may be secured to the sides 35 of the boiler (not shown), and vertical bars 12, secured to the platform 5, as shown in Fig. 2, either or both of said means may be employed for detachably securing the frame to the traction engine.

40 The frame further involves a broad cross bar or base 13, upon which a small double acting engine 14 is secured. Secured across the rear end of the frame is a broad flat bar 15 and therebelow a narrower flat bar 16. In the rear end of the frame are journaled two horizontal spaced rolls 17, and partly projecting rearwardly between said rolls are two vertical spaced rolls 18 mounted 45 between the plates 15, 16.

50 Guided between said four rolls is a cable 19, to whose rear end is fixed at 20 a shank 21, which has a slidable movement in a cylindrical sleeve 22 with a bell-shaped rear end 23 adapted to receive and guard the 55 opening of a hook 24, which is secured in the rear end of the slidable member 21;

said hook is adapted for engagement with the load to be hauled.

The front end of the cable is fixed to and wound upon a spiral-grooved drum 25, 60 which drum is axially threaded upon a screw 26, which is fixed to one or both of the frame bars 10 and is slidable on four parallel bars 27, which have their ends fixed in two gear-wheels 28, which are mounted 65 to rotate one upon each end of the screw 26 and are driven by two pinions 29 fixed on a shaft 30. Said shaft 30 is journaled upon the frame and is provided with a key 31, on which and on the shaft is slidably 70 mounted a clutch-member 32, which by a shifter lever may be thrown into a clutch member 34 formed on the hub of a worm-wheel 35, which normally rotates freely on the shaft 30 and is rotated by a worm screw 75 36 fixed on the crank shaft 14^a of the engine 14.

In order to get the cable 19 closely and neatly wound about the drum 25 also when there may be no rearward strain on it, I 80 provide a roller 37 to press downward upon about three of the last coils wound on the drum. Said roller is mounted in a forked lever 38, which is fulcrumed at 39 upon the frame bar 15, and has its rear end 40 supported by a strong spring 41 which presses the rollers 37 downward.

In the operation of the device, when the traction engine is drawing a threshing machine or separator or any other heavy vehicle, the pole of such vehicle is usually provided with an eye which is placed on the hook 24 and retained thereon by the funnel 23, and normally the hook is drawn and held as far as possible forward in the 90 funnel and the funnel as far forward as the cable guiding rolls 17 and 18 will admit. Now if the hauled vehicle encounters an obstruction, usually a soft portion of the road, which causes too great a resistance to 100 the forward progress of the traction engine, then the clutch member 32 is disengaged by the shifter lever so that the drum may unwind the required length of the cable while the engine moves forward to solid ground 105 some distance from the soft spot of the road, the clutch 32 is then thrown into action, the engine 2 may be stopped, and as the engine 14 is then started, the worm screw and worm wheel will wind the cable upon the 110 drum and thus pull the hauled vehicle over and beyond the soft place, or an upward

incline of road, while the traction engine itself serves simply as an anchor to the attachment. After the vehicle is thus brought on good road again, the secondary engine 14 is stopped and the main engine started again.

From the foregoing description it will be seen that the strain of the pulling cable does not tend to bend the screw 26, nor cause great friction on same, as said strain and friction are borne by and divided upon the four smooth bars 27 on which the drum slides. It will also be seen that by using a special engine for the attachment the work required of the attachment may be accomplished in but a fraction of the time it requires to perform it by a hand-operated attachment.

What I claim is:—

20 In an attachment for traction engines, a

frame, a screw fixed with its ends in the frame, a gear wheel journaled upon each end of the screw, a cable drum centrally threaded upon the screw and having in its heads apertures, a series of bars loosely 25 fitted in said apertures and secured with their ends in the said gear wheels, thus leaving the drum slideable on the bars, a shaft journaled in the frame parallel to the drum, two gear pinions fixed on the shaft 30 and meshing one with each of the gear wheels, and means for rotating the shaft alternately in opposite direction.

In testimony whereof I affix my signature, in presence of two witnesses.

GEORGE CUFF.
